(57) **CLAIM**

The ornamental design for a spring clamp jaw assembly, as shown and described.

DESCRIPTION

FIG. 1 is a perspective view of a spring clamp jaw assembly; FIG. 2 is a right side view thereof, wherein the left side view is substantially a mirror image of the right side view; FIG. 3 is a top view thereof, wherein a bottom view is substantially a mirror image of the top view; FIG. 4 is a front view thereof; and, FIG. 5 is a back view thereof.

The dashed lines form no part of the claimed design.
